(57) CLAIM

The ornamental design for a soap dispenser as shown and described.

DESCRIPTION

FIG. 1 is a perspective front view of a soap dispenser in a disassembled formation;

FIG. 2 shows a front view thereof;

FIG. 3 shows a rear view thereof;

FIG. 4 shows a left-side view thereof;

FIG. 5 shows a right-side view thereof;

FIG. 6 shows a top view thereof; and,

FIG. 7 shows a bottom view thereof.

The broken lines show portions of the soap dispenser that form no part of the claimed design.
